UNITED STATES PATENT OFFICE.

CHARLES PETERS AND ABRAHAM JACOBSON, OF LOS ANGELES, CALIFORNIA.

DESIGN FOR A SOUVENIR CLOCK-CASE.

46,578.

Specification for Design.

Patented Oct. 20, 1914.

Application filed May 25, 1914. Serial No. 840,856. Term of patent 3½ years.

To all whom it may concern:

Be it known that we, CHARLES PETERS and ABRAHAM JACOBSON, citizens of the United States, residing at Los Angeles, in the county of Los Angeles and State of California, have invented a new, original, and ornamental Design for a Souvenir Clock-Case, of which the following is a specification, reference being made to the accompanying drawing, forming a part thereof, and in which—

Our design as illustrated in the drawing is appropriate for and adapted to be used as souvenirs of the Panama California Exposition San Diego in 1915.

We claim:

The ornamental design for a souvenir clock case as shown.

CHARLES PETERS.
ABRAHAM JACOBSON.
